UNITED STATES PATENT OFFICE.

GEORGE MALPASS, OF PHILADELPHIA, PENNSYLVANIA.

DESIGN FOR A PEN.

SPECIFICATION forming part of Design No. 31,669, dated October 17, 1899.

Application filed July 12, 1899. Serial No. 723,619. Term of patent 14 years.

To all whom it may concern:

Be it known that I, GEORGE MALPASS, a citizen of the United States, residing in the city and county of Philadelphia, State of Pennsylvania, have invented and produced a new and original Design for Pens, of which the following is a specification, reference being had to the accompanying drawings, forming part thereof.

The leading feature of my design for a pen is a pen having a recess in the back thereof and a lip projecting from the front end of said recess rearwardly, said lip being of upwardly-curved or convex form in side elevation and overhanging said recess, imparting to the latter the appearance of a horseshoe-shaped slot as seen from the back.

Figure 1 represents a plan view of a pen embodying my design. Fig. 2 represents a section thereof on line $x x$, Fig. 1.

In the drawings, A designates a pen having a recess in the back thereof and a lip B, which projects from said back at the front end of said recess and is of upwardly-curved or convex form in side elevation, as a segment of a circle described from the under side of the back of the pen and projecting rearwardly and overhanging said recess, imparting to the latter the appearance of a horseshoe-shaped slot as seen from said back. 25

Having thus described my invention, what I claim as new, and desire to secure by Letters Patent, is—

The design for a pen substantially as shown and described.

GEORGE MALPASS.
